(57) **CLAIM**

The ornamental design for the combination container and frame, as shown and described.

DESCRIPTION

FIG. 1 is a top, front, and right perspective view showing the container portion of my new design for a combination container and frame.

FIG. 2 is a right side elevation view of the container shown in FIG. 1.

FIG. 3 is a left side elevation view of the container shown in FIG. 1.

FIG. 4 is a front elevation view of the container shown in FIG. 1.

FIG. 5 is a rear elevation view of the container shown in FIG. 1.

FIG. 6 is a plan view of the top of the container shown in FIG. 1.

FIG. 7 is a plan view of the bottom of the container shown in FIG. 1.

FIG. 8 is a top, rear, and left side perspective view of the upper portion of the container as it appears when separated from the lower portion.

FIG. 9 is a bottom front and left perspective view of the upper portion of the container portion shown in FIG. 8.

FIG. 10 is a top, front, and right perspective view of the lower portion of the container as it appears with the upper portion and packing frame removed.

FIG. 11 is a top, front, and right perspective view of the lower portion of the design with the packing frame in place.

FIG. 12 is a bottom rear and right perspective view of the lower portion of the container shown in FIGS. 10 and 11.

FIG. 13 is a top perspective view of the packing frame portion of the design as it appears when separated from the container, such appearance including the upper peripheral frame parts not shown in FIG. 12;

FIG. 14 is a right side elevation view of the packing frame shown in FIG. 13.

FIG. 15 is a left side elevation view of the packing frame shown in FIG. 13.

FIG. 16 is a front view of the packing frame shown in FIG. 13.

FIG. 17 is a rear elevation view of the packing frame shown in FIG. 13.

FIG. 18 is a plan view of the top of the packing frame shown in FIG. 13; and,

FIG. 19 is a plan view of the bottom of the packing frame shown in FIG. 13.
